UNITED STATES PATENT OFFICE.

CHARLES F. MEILINK, OF TOLEDO, OHIO, ASSIGNOR TO THE A. L. MOORE COMPANY, OF CLEVELAND, OHIO.

DESIGN FOR A THIMBLE FOR BICYCLE-FORK ENDS.

SPECIFICATION forming part of Design No. 26,360, dated December 1, 1896.

Application filed September 8, 1896, Serial No. 605,199. Term of patent 14 years.

To all whom it may concern:

Be it known that I, CHARLES F. MEILINK, a citizen of the United States, residing at Toledo, in the county of Lucas and State of Ohio, have invented and produced a new and original Design for Thimbles for Bicycle-Fork Ends, of which the following is a specification, reference being had to the accompanying drawings, showing the same.

In the drawings, Figures 1 and 2 are perspective views of a thimble for bicycle-fork ends embodying my design. Fig. 3 is a longitudinal central section of the same.

The leading features of my design are the tubular part A, having a closed button-shaped end B, the diameter of which is greater than

the diameter of the tubular part; the external annular shoulder C in the plane in which said head and tubular part meet, and a longitudinal slot D, formed in said head and extending, in both sides of the tube, past said shoulder.

What I claim is—

The design for a thimble for bicycle-fork ends, substantially as herein shown and described.

In testimony whereof I affix my signature in presence of two witnesses.

CHARLES F. MEILINK.

Witnesses:

E. L. THURSTON,
N. M. RANKIN.
